UNITED STATES PATENT OFFICE.

JACOB MUGGLI, OF ZURICH, SWITZERLAND.

MACHINE FOR CULTIVATING LAND.

996,998.

Specification of Letters Patent.

Patented July 4, 1911.

Application filed January 21, 1910. Serial No. 539,256.

To all whom it may concern:

Be it known that I, JACOB MUGGLI, a citizen of the Republic of Switzerland, residing at Nägelistrasse 8, Zurich, Switzerland, have 5 invented certain new and useful Improvements in Machines for Cultivating Land; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 The subject of my invention is an improved method of, and machine for, cultivating land.

According to the new process the ground is mechanically scraped by means of suitable 20 implements, and the soil so scraped is thrown upward.

The machine for carrying out the process is furnished with an endless apron, which can be set in motion by means of a motor, 25 employed to drive the machine. On this apron the operative implements are disposed in such manner that they can yield in all directions.

Certain practical embodiments of the in- 30 vention are illustrated in the accompanying drawing.

Figure 1 is an elevation, showing one form of construction of the machine, such parts as are not necessary for explanation of the 35 invention being omitted. Fig. 2 is a plan of the left-hand portion of Fig. 1, a part of the apron being broken away to display underlying parts. Fig. 3 is a vertical sectional view illustrating a modified construc- 40 tion of drum with sieve. Fig. 4 is a front view of a sinuous sieve. Figs. 5-9^a show various forms of implements. Figs. 10-15 illustrate several forms of construction of the endless apron. Fig. 16 illustrates dia- 45 grammatically two ways of disposing the implements upon the endless apron.

Referring to Figs. 1 and 2, there are provided at each side of the frame 1 of a motor-cart, bars 2 whose upper ends are journaled 50 on the pins 3, while the other ends are connected by a shaft 5. On the one pin 3 there is mounted a sprocket-wheel 4, which is driven by the motor, through the agency of means not shown, and whose chain 6 runs over a sprocket-wheel 7, keyed to the shaft 5. To the shaft 5 there is also keyed a

trundle-drum 8. Further, there is loosely mounted on this shaft 5 the one end of each of two short frame-bars 9, while the other ends of these bars are connected by a shaft 10. Between the bars 9 there is mounted a roller 12 loaded with weights 11. On the shaft 10 there is mounted a second trundle-drum 13. Around the two drums 8, 13 there runs an endless apron 14, provided with scrapers 15. 16 are ropes for elevating the frames 2 and 9, and the dot-and-dash lines in Fig. 1 show the frame 9 in its raised position. 17 are arms extending rearwardly of the drum 8 for the purpose of sustaining 70 a sieve.

When the sprocket-wheel 4 is driven by the motor, the drum 8 revolves and drags the network 14 over the ground. The scrapers thus dig into the soil, rake along 75 the scraped material, and throw it up behind the drum 8. Should there be stones in the way, the scrapers will pass over or around them, as the network admits of their yielding in all directions, so that the stones 80 will gradually loosen and be carried along by the scrapers. The network during such working adapts itself to the surface of the ground. If the latter should be so hard that the momentum of the apron is insufficient to 85 enable proper operation of the scrapers, the roller 12 must be lowered upon the apron, so as to load it. If the soil is to be scraped to a very considerable depth, the frame 9 must be drawn up, whereby the area of the 90 scraping-surface is diminished, while the pressure at the place of work is increased.

Referring now to the modifications shown in Fig. 3, the network 14 is passed around merely a single drum 8, which rotates with 95 the shaft 5. On this shaft, at a suitable distance apart, two polygonal disks are secured, which at their corners are united by trundles 19, so that a kind of reel is constituted. The trundles 19 are held by adjustable brackets 100 20. Around this reel the network 14 is applied, and rigidly or resiliently connected with the trundles 19 at suitable places. When the reel 8 rotates, the network 14 has the tendency to fly out from the center of rotation; it thus bears closely against the ground and scrapes away everything that obstructs it. The material is thrown up in the same manner as in the construction with two drums. In both cases, and also with 110 other arrangements of the scraping-network, individual portions of the latter can, if

strained by pull, jerk, pressure or recoil of the scrapers, yield independently of each other, and in the course of the rotation return automatically into their normal position, owing to the centrifugal force.

The scraping-network can, as Figs. 10 and 11 show, consist of the bases of the scrapers themselves, which may be jointed (e. g. by means of wires), to each other. Or the scrapers may be set in chains or netted work of well-known description, and connected therewith with capability of free movement, or hung therein (as shown in Figs. 12 and 13). The network may also consist entirely (Fig. 14), or partly (Fig. 15) of springs. In the case of sandy soils relatively blunt scrapers prove adequate. If, however, turf, foliage, stubble, stalks, or the like, have to be cut through, such obstructions must first be reduced, that is, the scrapers must break them through and then cut them, before they are mixed with the soil. In such cases, scrapers with cutting-edges, as for example as those shown in Figs. 5 and 6, should be employed. If the scraping network is to be employed for various classes of work, the scrapers must be so secured as to be readily removable. This is requisite, for instance when the scrapers have also to scrape manure, conveyed by the cart and mix it with the soil.

In the present method, the earth is not cut out in cylindrical pieces (as is the case with prior machines, which do not scrape, but rather dig and pierce), but is removed in a form suited to the resistance offered by the soil, and repeatedly changing.

The scraped material may be thrown up in the following manner: The remnants of vegetable matter (Fig. 1) are overcome by the resistance of the air and rapidly fall to the ground. Fine, pulverized earth y likewise descends rapidly. Clods and stones z , on the other hand, are hurled to a great distance and fall out on top at the back. In autumn, and in turning over frosty land, this method of working may be suitable; in warmer countries and for sowing, it would be suitable, as in such case it is the fine earth that is required on the top. For this purpose sieves 23 (Fig. 3) are stretched between the arms 17. If these sorting-sieves 23 are flat, the scraped material passing through them will naturally lie evenly on the land. The clods and stones being the heaviest bodies are hurled to the highest part of the sieve, but cannot drop through the meshes and must therefore return and have a considerable distance to travel. They therefore fall in front of the sieve, at the deepest

place. The pulverized earth y on the other hand, together with the small broken pieces of the clods, passes through the sieve, and as the cart advances, covers the clods and stones. In this manner the fertile mold 65 comes to the surface. If sinuous sieves are employed (Fig. 4), the coarse pieces of earth collect in the grooves 28 and form on the land, ridges 29 which are covered with fine material. In this way the furrows necessary for the protection of various cultures can be formed, and these can be simultaneously sown by a drill, hung above. In this manner naturally only fine earth collects in the furrows, while the ridges are 70 built up of coarse material also. As Fig. 16 shows, different kinds of scrapers may be disposed at definite parts of the apron. 75

I claim as my invention—

1. A machine for cultivating land, comprising a machine-frame, a roller-frame pivoted to the machine frame, rollers carried by the said roller-frame, means for imparting motion to said rollers, an endless belt or apron passing over said rollers, and 80 scrapers attached to said endless belt in such a manner that they are free to move in any direction.

2. A machine for cultivating land, comprising a machine-frame and roller-frame pivoted to the machine-frame, rollers carried by the said roller-frame, means for imparting motion to the said rollers, an endless belt or apron passing over said rollers, scrapers pivotally attached to the said endless belt which latter is in the shape of a 90 net-work. 95

3. A machine for cultivating land, comprising a machine-frame, a roller-frame pivotally connected to the machine-frame, rollers mounted in said roller-frame, means for actuating the said rollers and means for elevating one of the said rollers so as to throw the entire weight on the other roller. 100

4. A machine for cultivating land, comprising a machine-frame, a roller-frame pivotally connected to the machine-frame, rollers mounted in said roller-frame earth engaging means on said rollers, means for actuating the said rollers, and a sinuous-shaped sieve located rearward of the said rollers. 105 110

In testimony that I claim the foregoing as my invention, I have signed my name in presence of two subscribing witnesses.

JACOB MUGGLI.
